OF MAINE.

LAST.

No. 914,329.

Specification of Letters Patent.

Patented March 2, 1909.

Application filed December 22, 1908. Serial No. 468,821.

To all whom it may concern:

Be it known that we, ELMER J. BLISS and EDWARD F. WHITE, citizens of the United States, and residents of Edgartown, county 5 of Dukes, and Quincy, county of Norfolk, Massachusetts, have invented certain new and useful Improvements in Lasts, of which the following is a specification.

This invention relates to lasts used in the manufacture of boots and shoes and is intended to provide a simple and effective construction for overcoming certain difficulties encountered in the manufacture of boots and shoes in which the measurement of the ball 10 portion of the shoe is considerably greater than the measurement of the waist portion behind it.

In a normally shaped foot the girth or circumferential measurement of the ball is 20 quite appreciably larger than the girth of the waist of the foot. In order to properly support and sustain the foot in the shoe, the waist portion of the shoe should snugly fit and hold the waist portion of the foot while 25 the ball portion farther forward of the shoe should afford ample room for the spreading of the ball of the foot upon which the weight rests in walking. The difficulty in properly constructing a shoe to entirely meet these requirements is due to the fact that if the ball 30 of the last is made considerably larger than the waist the withdrawal of the last causes the large ball to break down or stretch out of shape the narrow waist of the shoe. If the 35 foot should be slightly abnormal as would be the case when a bunion is formed on the ball of the foot the difficulty is still further increased.

This invention consists of a last whose fore 40 part is divided into two completely separable sections which are held together when in normal position in the shoe by retaining devices which form an adequate support to resist the heavy pressure during the leveling and other 45 operations, while allowing one section to be withdrawn independently of the other.

In the accompanying drawings we have 50 illustrated two forms of lasts embodying the principle of this invention.

Figure 1 is a side elevation partly in section of a hinged last containing the invention. Fig. 2 is a plan view thereof. Fig. 3 is a side elevation of a sectional last having a

removable instep block. Fig. 4 is a plan view thereof.

In the practice of our invention as illustrated in Figs. 1 and 2, the last is divided into a heel block *a* and a fore part which is divided into a main section *b* and a smaller side section *b'* by longitudinally and transversely extending cuts or dividing planes. Projecting forward from the transverse plane of the main section *b* is an elongated rod or pin *c* which preferably extends more than half way from the transverse wall to 60 the toe and in a plane parallel to the longitudinal plane of division. Adjacent to the retaining pin *c* is a shorter parallel pin *c'*. The side section *b'* of the fore part is provided with recesses *c²* and *c³* of unequal 65 length extending longitudinally from the rear wall or face to receive the projecting pins *c c'*. The pins are preferably made of metal or like substance and by extending the pin beyond the middle of the side block, a support is given to the side block for the greater 70 part of its length which holds it firmly against the very heavy pressure to which the last is subjected in leveling and other operations, while the smaller pin *c'* acts to hold the side 75 block against rotation or twisting movement to prevent its gaping open along the line of the divisional longitudinal cut. The heel block in Figs. 1 and 2 is hingedly connected to the main section of the fore part as indicated at *a'*, the hinge being normally held in open or extended position by means of the 80 spring-pressed plug *a²*. In order to prevent the adhering of the two sections of the fore part, we provide a spring-pressed plug or 85 plunger *d* which is seated in a socket formed in the transverse face of the fore part in position to exert a forward thrust or push 90 against the rear face of the side section *b'*. This starts the separation of the parts during 95 the initial rearward movement of the last, while the sliding engagement formed by the holding pins *c c'* with the side section permits a complete separation of the two sections of the fore part.

In Figs. 3 and 4 we have shown the heel portion of the last formed integral or solid with the fore part and have shown the fore part provided with a removable instep block *e* lying chiefly or wholly on one side of the 105 center so that when the instep block *e* is

withdrawn it is possible to lift the heel portion of the last to withdraw the main portion in advance of the separable side section.

It will be observed that in both forms of last, the transverse cut is back of the ball portion so that the longitudinal cut extends through the middle portion of the ball in order that the width and consequently the girth of the ball shall be diminished as the sections are separated. By this principle of construction any desirable degree of contraction of the ball may be secured to completely avoid the breaking down of the waist. As the sections are capable of complete separation, the side section remaining in the shoe while the main section is withdrawn, there is no limit within practical requirements of the amount of contraction attainable.

What we claim is:—

- 20 1. A last whose sectional fore part is divided vertically by longitudinal and transverse cuts, the main section being provided with forwardly projecting holding pins of unequal length arranged to extend into longitudinal recesses formed in the side section parallel to the longitudinal dividing plane to afford a sliding and retaining engagement between the two sections, substantially as described.
- 25 2. A last having a sectional fore part divided vertically by longitudinal and transverse cuts, the main section being provided with a forwardly projecting pin extending parallel to the longitudinal division for the greater part of the distance to the toe, the side section being provided with a corresponding longitudinal recess for the greater part of its length to receive said pin, and

means for preventing the side section from turning about the holding pin, substantially as described.

3. A last having a sectional fore part divided vertically by longitudinal and transverse cuts into two sections and longitudinal pins of unequal length extending parallel to the plane of longitudinal division to form a sliding engagement and support between the two sections while permitting their separation, substantially as described.

4. A last having a sectional fore part divided vertically by longitudinal and transverse cuts, a longitudinal pin secured in the transverse face of the main section and extending for the greater part of the distance to the toe parallel to the longitudinal plane of division, the side section being provided with a corresponding recess to receive said pin so as to be supported thereby the greater part of its length, and means tending normally to separate the sections, substantially as described.

5. A last embracing a sectional fore part divided vertically by transverse and longitudinal cuts into two sections having longitudinal sliding engagement with each other, the main section being provided with a separable instep block cut away chiefly on the side opposite to the sliding side section, substantially as described.

In witness whereof, we have subscribed the above specification:
